UNITED STATES PATENT OFFICE.

PAUL KESTNER, OF LILLE, FRANCE.

PROCESS FOR THE PREPARATION OF SUGAR IN THE FORM OF FINE CRYSTALS.

1,149,067.

Specification of Letters Patent.

Patented Aug. 3, 1915.

No Drawing.

Application filed July 17, 1914. Serial No. 851,473.

To all whom it may concern:

Be it known that I, PAUL KESTNER, a citizen of the French Republic, residing at Lille, in the Nord Province of France, have 5 invented a new and useful Process for the Preparation of Sugar in the Form of Fine Crystals, of which the following is a specification.

This invention has reference to a process 10 for the preparation of sugar in the form of fine crystals and its object is to prepare by mechanical means the sugar in the form of flour known as Brazilian sugar or "aréado" which is now produced by working up melted sugar rapidly while allowing it to cool. Hitherto so far as I am aware no one has succeeded in bringing about mechanically this phenomenon of crystallization in a satisfactory manner, and in Portugal and 15 Brazil, the countries of origin of this sugar, it is still produced by the workmen operating the pans by hand. I have found as the result of experiments that this crystalline formation can be brought about mechanically by causing melted sugar containing only a small percentage of water to flow in a thin layer on to a plate to which a rapid vibratory movement is imparted. In cooling 20 upon the vibrating plate, the sugar crystallizes in the form of flour. My process 25 enables this kind of sugar to be readily produced on a large scale. All that is necessary is to provide a sheet metal or like table to which, in any known manner, a rapid vibratory movement is imparted, and to allow 30 a thin layer of the melted sugar to flow on to the table. The process may be a continuous

one if the table be inclined slightly, or if an endless band be employed in place of table, or if the table be constructed on the principle of the well known Kreiss jerking conveyor.

What I claim as my invention and desire to secure by Letters Patent is:—

1. A process of producing sugar in the 45 form of fine crystals or flour, consisting in causing melted sugar to flow on to an approximately horizontal surface and imparting rapid vibratory motion in an approximately horizontal plane to the said surface. 50

2. The process of producing Brazilian or "aréado" sugar which consists in causing melted sugar containing only a small percentage of water to flow in a thin layer on to an approximately horizontal surface and 55 imparting rapid vibratory movements in an approximately horizontal plane to the said surface while allowing the sugar to cool thereon.

3. A continuous process for the production 60 of Brazilian sugar, consisting in causing melted sugar to flow in a thin layer on to an endless traveling band and imparting rapid longitudinal vibratory movements to the said band while allowing the sugar to 65 cool thereon.

In testimony whereof I have signed my name to this specification in the presence of two subscribing witnesses.

PAUL KESTNER.

Witnesses:

LÉON PECKEL,
VICTOR KLAUSZMANN.
